UNITED STATES PATENT OFFICE.

JOHN H. MACALMAN, OF SOMERVILLE, MASSACHUSETTS.

DESIGN FOR A VEHICLE-BODY.

SPECIFICATION forming part of Design No. 35,910, dated May 13, 1902.

Application filed December 19, 1901. Serial No. 86,619. Term of patent 7 years.

To all whom it may concern:

Be it known that I, JOHN H. MACALMAN, a citizen of the United States, residing at Somerville, in the county of Middlesex and State of Massachusetts, have invented and produced a new and original Design for a Vehicle-Body, of which the following description, in connection with the accompanying drawing, is a specification, like letters on the drawing representing like parts.

The drawing, in isometric perspective, shows my new design.

As shown in the drawing, the leading or material feature of my design consists of the body proper, having substantially parallel top and bottom lines *a b*, with the oppositely and inwardly inclined front and rear lines *c d*. The top line *a* of the body is surmounted by a horizontal rail *e*, curved downwardly and inwardly in a scroll at each end to meet the body, with a vertically-standing back *f* sub-

stantially midway between the said front and rear lines *c d*.

At its front the body is provided with an extended foot portion *g*, terminating in a ²⁵ dasher or front box-shaped to present substantially vertical front and rear lines *h i*, the latter meeting the foot portion in a gradual sweep *i'*, and the forwardly and upwardly curved concave top line *j* and bottom line *k*. ³⁰

Having described my invention, what I claim as new, and desire to secure by Letters Patent, is—

The design for vehicle-body as herein shown and described.

In testimony whereof I have signed my name to this specification in the presence of two subscribing witnesses.

JOHN H. MACALMAN.

Witnesses:

EVERETT S. EMERY,
A. E. CHESLEY.
